CARD OPERATED SENSING MEANS

Joseph B. Lohr, Wayne, and Preston E. Zink, Mount Tabor, N.J., assignors to Monroe Calculating Machine Company, Orange, N.J., a corporation of Delaware

Filed Nov. 23, 1960, Ser. No. 71,345

1 Claim. (Cl. 235—61.11)

The present invention relates to improvement in record card operated sensing means of the star wheel type which are rotated for effecting a series of electrical impulses while the record cards are in motion through the usual card feeding mechanism associated with accounting and statistical machines.

In particular the invention provides for improvement in a sensing means such as that which is disclosed in the U.S. Patent 2,938,667, issued to Fritz A. Deutsch May 31, 1960. As set forth in said patent, data to be analyzed by the sensing devices usually appear as perforations effected in successive vertical columns of a punched record card provided with data index positions located in horizontal rows and vertical columns, the data being represented in columns of the record card in accordance with a chosen code. The cards are conveyed along suitable guide means to pass a sensing station which may comprise a line of individual star wheel type sensing members, one for each of the indicia recording horizontal rows of the card. At this sensing station, perforations in the record card will operate the start wheels which cause opening and closing of individual related contact members for effecting electric circuits utilized to control various accumulating, printing and other related mechanisms, in well-known manner.

Where a series of closely spaced perforations appear upon a record card the start wheels are rotated continuously thereby and will effect a series of electrical impulses in accordance therewith. In the above patent this is accomplished by engagement of the spokes of any rotating star wheel with a suitable cam element which causes the wheel to be oscillated bodily for making and breaking related contact members and so effect an electrical pulse for each step of movement of a star wheel by the card perforations.

Record cards may contain any desired number of record columns, one complete card of well-known type containing 80 columns, which may be divided selectively into a plurality of fields each employing one or more record columns as desired. Thus it may be that a considerable portion of a record card remains unpunched, and as the card is fed past the sensing station the start wheels will rest upon the unpunched surface of the card in a sliding engagement therewith. In actual practice it has been found that the coefficient of friction between the star wheels and a record card may frequently vary, this probably being caused by changes in climatic conditions and by the various dyes used when coloring the cards for code identification. Thus at times such frictional engagement is sufficient to cause one or more of the sensing wheels to be rotated by an unpunched portion of a card, whereby errors in the pulsing signals are liable to occur.

It is an object of the present invention to prevent such misoperation of the sensing means by the provision for positive stop detent means which act to cooperate automatically with a star sensing wheel and to prevent a rotation thereof only under such condition as wherein the sensing wheel rides upon the card surface.

Another object of the invention provides for a fixed stop means which will automatically interrupt the rotation of any star wheel as said wheel is displaced to a given position when sensing a nonperforation in a card during operations thereof and which stop means permits a sensing rotation of the star wheel at other displaced positions thereof.

2

The above and other objects, features, and advantages of the present invention will be more fully understood from the following detailed description when considered in connection with the accompanying drawings which form a part of the specification.

In the drawings:

FIG. 1 is a vertical cross section of a star wheel record card sensing device embodying the invention, the parts being in their normal lower position of rest and with a record card shown making a first contact with a tooth of the sensing wheel.

FIG. 2 is an enlarged detail elevation showing a star wheel in a partially raised condition to that of FIG. 1, as would occur when said wheel rotates past the high point of a control cam during operations thereof by a record card.

FIG. 3 is a view similar to FIG. 2 but showing the star wheel raised to a higher position, as when a pair of radially adjacent teeth thereof come to rest upon the top surface of a record card.

FIG. 4 is a view similar to FIG. 3 but showing the star wheel in yet another position, as when during an operation a tooth thereof enters a first perforation of the record card.

FIG. 5 is a fragmentary plan view showing a plurality of the sensing members.

As fully described in the above referred to Patent 2,938,667 record cards 20 are fed seriatim from a suitable hopper and into a passage 22 formed by guide plates 23, 24 along which the cards move past a sensing station represented in general by a row of separate sensing elements 25 of a well-known star wheel type. For the purpose hereinafter to be described however the devices of the present application include start wheels which comprise five teeth in lieu of the six teeth of the wheels shown in said patent. The sensing wheels 25 extend in a line transversely of the passage 22 and correspond in number and position to the twelve index point positions of a record column of the well-known cards. Each sensing wheel 25 controls the opening and closing of an individual related contact element 63 and so will directly effect thereby a series of electrical impulses to related read-out circuit leads 127, said impulses being in accordance with a series of data perforations within a selective group of columns on the card sensed by the related wheels 25 during a movement of the record card past the sensing station, as in the manner fully set forth in said reference patent.

The sensing wheels 25 are each rotatably mounted upon the remote end of related levers 64 fulcrumed upon a transverse rod 65 supported within the ends of a transverse frame 66 mounted above the upper surface of the guide plate 23, which plate together with bottom guide plate 24 forms the record card feed passage 22. Upon the opposite end of each of the levers 64 is mounted an insulation block 67 each having engagement with a related one of the contact elements 63 above set forth. The contact elements 63 are formed of spring stock and all suitably anchored within a common contact bar, not shown. Contact elements 63 are constantly urged toward engagement with related contact studs 69 mounted within the frame 66 and each electrically insulated thereof through means of suitable insulation collars 70. Thus in the normal position of the parts, illustrated in FIG. 1, contact elements 63 will serve to hold each of their related levers 64 in a clockwise position, wherein one tooth 25b of a pair of angularly adjacent teeth of the five-tooth star wheels 25 is held into engagement with an upper surface 71 of a transverse plate 72, secured to the bottom surface of the guide plate 24. The tooth 25a of said pair of teeth has engagement with a surface 71' of the plate 72, said latter surface being in a plane perpendicular to the plane of surface 71. Thus a cam surface 73 of said

plate formed at the apex of said surfaces is adapted to extend within the space as formed by a pair of adjacent teeth of the star wheels 25.

As a record card 20 is fed along the passage 22 a leading edge of the card will effect engagement with the tooth 25b and will rotate the wheel 25, so that said tooth engaging cam surface 73 will rock the related lever 64 in a counterclockwise direction, as tooth 25b rotates to the position illustrated in FIG. 2. There will be no perforations in the marginal portion of the record cards and as the card movement continues to rotate the wheels 25, a next succeeding tooth 25c of each of the wheels engages the marginal top surface of the card and will rock the respective levers 64 to a further counterclockwise position, as illustrated in FIG. 3 wherein adjacent teeth 25b-25c of the wheels 25 rest upon the card. In the above operations all of the contact elements 63 are thus caused to be rocked downwardly out of engagement with their respective contact studs 69. Immediately thereafter live circuit is caused in any suitable manner to be extended in common to all the contact elements 63. As a record card continues in movement past the sensing station the record columns are brought successively into sensing position and where the corresponding index point position contains a code hole the tooth 25c of the related star wheel 25 will first enter such hole until stopped by engagement with the surface 71 of plate 72, as illustrated in FIG. 4, the said surface being spaced slightly below the card bottom surface. Thereafter the card movement will rotate tooth 25c over the cam surface 73 of plate 71 and cause a reciprocatory movement to be effected to the related lever 64.

From the foregoing it will be apparent that code perforations may be spaced within a card at wide intervals or in a series of closely spaced intervals and that operations as effected by such perforations to the star wheels 25 will, through means of cam member 73, cause a corresponding series of oscillations to be effected to the related levers 64. Such oscillations of lever 64 are adapted to effect a corresponding series of make and break operations to the related contact elements 63 for directly effecting thereby a series of electrical read-out impulses which are to be selectively transmitted to the usual relay devices adapted for controlling operations of a tabulating machine or the like in the well-known manner.

To prevent mutilation of the card edges at the perforations it is essential that the star sensing wheels be as freely rotatable as possible. Also the resilient contact spring members 63 should be as light as possible consistent with holding the star wheels in proper engagement with any record card.

Where code perforations are spaced at a wide interval it is intended that the record card be advanced while a pair of adjacent teeth of the star wheels rest in a slideable engagement upon the upper card surface in such manner that no rotation is effected thereto by the card surface.

It has been found, however, that frequently irregularities will occur in the record card surfaces, which may be due to atmospheric conditions or by reason of certain dyes used in coloring the cards for identification. Thus, at times, the coefficient of friction of a card with a sensing wheel may be sufficient to cause the wheel to be rotated by the card surface. Such operations are immaterial if no card perforation is involved, since the lever 64 remains in raised position sufficient to maintain contact 63 free of the contact 69. However, if such an operation should occur at any time that a card perforation is being brought to the position for engaging a tooth of the star wheel, said wheel may be in a partly rotated condition and thereby will be out of time for proper engagement with the perforation. Thus an advancing tooth of the wheel may bridge the intended card perforation and a pulsing signal will be lost.

While spring detent means are well known which may be utilized to engage with the star wheels for retarding a

rotation thereof such means are objectional in that by loading up the wheel they will cause damage to occur to the edge of the card perforations during the operations thereof.

Applicants provide the following very simple control means which is adapted without increasing the load of the star wheels to act automatically for preventing such misoperation of the star wheels by positively preventing any mistiming of the wheel with respect to an engagement thereof with a card perforation.

Extending transversely of the star wheels 25 is a plate 75 which is fast within the left and right support frames 66. The lower end of plate 75 has a finger 76 which projects downward at an angle and terminates at a fixed position for cooperating with any one of the teeth of the star wheels 25 in the following manner.

Upon movement of a record card which advances the star wheels 25 from their normal position of rest, shown in FIG. 1, to pass over the high point of cam 73, as for the position illustrated in FIG. 2, the tooth 25d of each wheel is caused to move in a path as indicated by the broken line 74 in FIG. 1. Thus at this time the teeth of the star wheels are permitted to rotate freely and pass beneath finger 76. In a continued movement of said star wheels, whereby a pair of adjacent teeth thereof are brought to rest upon the surface of a record card, as earlier described, the wheels are caused to be raised and any succeeding tooth 25e thereof is moved thereby to a raised position slightly to rightward but still free of the finger 76, as shown in FIG. 3. If now in a further movement of the record card a sufficient friction between the card and tooth 25c is generated to rotate the wheel 25, the tooth 25e thereof, unless otherwise prevented, would move in a path indicated by the broken line 77 of FIG. 3. However, in the devices of the present invention finger 76 is adapted under the above conditions to intercept such a movement of tooth 25e and will prevent rotation of the star wheel at this time. Thus an advancing card perforation will now engage the respective tooth 25c of any star wheel uniformly at a given point for proper timing relation therewith and will thereby prevent the previously described misoperations as would otherwise occur.

As a card perforation moves into position for engagement by a tooth 25c said tooth in entering the card perforation will first permit a slight downward movement of the related wheel 25 with its lever 64, and tooth 25e is caused to be moved downwardly and free of the finger 76, as shown in FIG. 4. Thereafter as a series of closely spaced perforations successively engage each succeeding one of the teeth for rotating the star wheel any upper tooth corresponding to the tooth 25e will each time be operated in a path of movement free of the finger 76.

It will now be apparent that applicants' novel devices provided for means which in very simple manner will act to automatically and positively prevent the operation of a star sensing wheel at such time as when a misoperation may occur thereto and which permits also without any additional load thereon any regular operations of the said wheels as effected in the normal operations thereof.

While the above description sets forth a preferred embodiment of the invention and the manner of use to which it is to be put, it will be understood that the invention is not limited to the precise form disclosed, but is susceptible to embodiment in various other forms.

What is claimed is:

In a card sensing device having a plurality of multi-tooth sensing wheels selectively rotatable by record card perforations during an advancing movement of the card: the improvement comprising a fixed control member in common to said sensing wheels and being normally free of the teeth thereof whereby to permit said rotation of said wheels, and wherein during such rotation said sensing wheels are adapted to be lifted by said advancing movement of the record card whereby to position a pair

of adjacent teeth of selected ones of said sensing wheels for sliding support upon the upper surface of a record card, and in which any given tooth of any sensing wheel is brought thereby into juxtaposition for a subsequent cooperation with the said fixed control member and wherein during a subsequent advancing movement of the record card frictional engagement therewith tends to further rotate and lift the said sensing wheels for engaging the said given tooth thereof with said fixed control member, and in which said fixed control member thereupon in a positive manner will prevent such a further rotation of any ones of said sensing wheels, and control

means of said record card cooperable with any said sensing wheels for releasing selective ones thereof from said control member during a further advance of the record card, said last mentioned control means comprising the selectively spaced perforations in the said record card.
